UNITED STATES PATENT OFFICE

ROBERT G. MERRITT, OF KENSINGTON, MARYLAND

SUBMARINE CLOSURE

Application filed June 13, 1928. Serial No. 284,972.

This invention relates in general to submarine devices and more particularly has reference to a closure for allowing a diver attached to lines communicating with an outside source, to enter or leave a submerged compartment.

The invention forming the subject matter of this application is a continuation in part of an invention disclosed in my copending 10 application for Letters Patent, identified by Serial No. 254,029, and entitled "Submarine devices." My parent application is directed to an apparatus for rescuing crews entrapped in sunken submarines or other vessels.

The invention consists in general of the provision of an apparatus in the form of a cylindrical container composed of material having a substantially greater density than 20 that of sea water and constructed to withstand the range of pressures to which it may be subjected. The container is designed to receive one or more divers equipped for carrying on rescue operations, and in addition, to accommodate a substantial number 25 of any entrapped crew that may be removed from a submerged vessel.

The container is fitted with a top closure and a closure near the bottom, both operable 30 from within, adapted to seal off the interior of the container from the surrounding aqueous medium. A resilient cup is attached to the lower end of the container in line with the bottom closure, for the purpose of effecting 35 a seal with the hull of a sunken vessel, and provided in addition around the walls for fixing the container in position after it has been lowered in place.

The shell of the apparatus is formed for 40 receiving a plurality of conduits to admit air in the container and to the diver or divers enclosed therein, through lines communicating with an outside source. The container is 45 adapted to be lowered from the surface with the closures open and made fast to the vessel with the cup against the hull; whereupon, the top closure is sealed and the water exhausted by suction through the lines with the 50 concomitant admission of air thus effecting

a vacuum seal between the cup and the hull of the vessel.

The diver or divers in the container may reach any entrapped occupants by cutting or otherwise penetrating the portion of the hull exposed within the cup so that any crew within may be removed to the interior of the container. When it is desired to raise the apparatus to the surface, the bottom closure is sealed and fluid pressure introduced in the cup, thus breaking the seal and allowing the container to become detached from the vessel. 55 60

In the preferred construction, the apparatus takes the form of a cylinder, in order that it may meet with the least possible hydrostatic resistance on being lowered in the water, although such a shape is not essential, and likewise, while it is deemed desirable to make up the container of a substantially uniform diameter, any other shape found more 65 suitable for particular operations may be employed. When the container is submerged, the closures, as previously stated, are left open, so that the container acts as a cylinder 70 open at each end, and hence is buoyed only by a force equal to the weight of the displaced liquid. On ascending to the surface, as the water in the container is exhausted, it is thus buoyed up by an increased pressure 75 which is equal to the weight of the volume of water removed, the degree of buoyancy varying with the dimensional characteristics of the particular construction. 80

It will be apparent that the field of a diver 85 enclosed in the container is restricted to the length his lines extend through the conduits, thus making it necessary for other divers to carry on operations outside of the apparatus. This same difficulty is likewise encountered in all the various types of undersea apparatus 90 now commonly employed, inasmuch as the respiratory and other lines communicating with an outside source are fixed through the apparatus.

An object of this invention is to provide a 95 closure for the apparatus disclosed in my copending application, to allow a diver attached to lines communicating with an outside source to enter or leave the container while it is submerged. 100

Another object of this invention is to provide a submarine compartment in which a diver attached to lines communicating with an outside source may leave or enter.

5 A further object of this invention is to provide a closure for a submarine compartment which may be entered by a diver attached to lines communicating with an outside source, and the water in the compartment exhausted 10 without subsequent leakage.

10 With these and other objects in view which may be incident to my improvements, the invention consists in the parts and combinations to be hereinafter set forth and claimed, 15 with the understanding that the several necessary elements comprising my invention, may be varied in construction, proportions and arrangement, without departing from the spirit and scope of the appended claims.

20 In order to make my invention more clearly understood, I have shown in the accompanying drawings means for carrying the same into practical effect, without limiting the improvements in their useful application 25 to the particular constructions, which for the purpose of explanation, have been made the subject of illustration,

In the drawings forming a part of the specification, Figure 1 is a longitudinal sectional view of the closure forming the subject matter of this invention, showing lines communicating with an outside source, attached to a diver's helmet.

Figure 2 is a sectional view taken on line 30 2—2 of Figure 1, looking in the direction of the arrows.

Figure 3 is a top view taken on line 3—3 of Figure 2 looking in the direction of the arrows.

40 Figure 4 is a perspective view showing the manner in which the plug carrying the lines communicating with an outside source, is fixed in the rim of the closure.

Referring by numerals to the drawings in 45 which the same and similar elements are designated by like symbols of reference throughout, and more particularly to Figure 1, there is shown a container having cylindrical side walls 1 forming a compartment 2. 50 This container may, for the purposes of the present description be considered the same as that shown in my copending application, although, as will appear hereinafter, the closure is susceptible for a wide range of usage 55 with other types of apparatus.

The container is provided at the top with an inwardly extending flange 3, which may be integrally constructed with or otherwise 60 fixed around the side walls 1, or as will be more particularly pointed out later, may constitute a portion of the hull of a submersible vessel. The flange 3 terminates in an upwardly extending rim 4, upon which there is 65 adapted to be seated a rim 5 projecting down-

wardly from and formed integral with a closure 6.

The rim 5 is held on the rim 4 by hinge members 7 and 8 welded or otherwise securely attached to the outside of the respective rims, and pivoted on a pin 9. The faces of the rims 4 and 5 are formed with tapered annular grooves 11 and 12 in which there are adapted to be seated a plurality of gaskets 13 and 14 extending above the surface of each rim, so that when the rim 5 is locked on the rim 4, the gaskets will be compressed and a water-tight seal insured.

70 The sides of the respective rims opposite the hinge connection are formed with oppositely disposed projections 15 and 16, as shown in Figures 3 and 4. The projections are formed with tapered depressions 17 and 18 communicating with longitudinal depressions 19 and 21 formed across the rims, so that when the closure is in place an aperture 22 having a tapered neck 23 is formed, as shown in Figure 4. A plug 24, composed of any suitable resilient material such as rubber, and preferably of variable plasticity progressively more resilient from the center outward, 75 is adapted to fit in the aperture 22 and thus seal the closure. The plug 24 is formed with a neck 25 adapted to fit in a tapered seat 23 formed by the tapered depressions 17 and 18 in the projections 15 and 16 so as to prevent it being pushed in the container by the water pressure when the apparatus is submerged.

80 The rim 4 is formed with an inwardly extending neck 26 having a depression 27 communicating with the depression across the rim adapted to receive the end of the plug 24. A plurality of hinge projections 28 and 29 are formed on the top of one side of the neck and one end of a spring 31, conforming with the shape of one-half of the diameter of the plug pivoted thereon by a pin 32. The opposite end of the spring 31 is formed with a flange 33 adapted to engage a hook 34 pivoted in a groove on the other side of the neck 26 by a pin 35. The hook 34 is formed with an integral arm 36, so that after the flange 33 on the spring 31 is snapped in place, it may be disengaged by pressing the arm against the pressure of a leaf spring 37 mounted in 90 the groove in back of the arm 36.

95 It is to be noted that the gaskets 12 and 13 seated in the rims fit around the depressions. In this manner when the plug 24 is inserted and locked in place by the spring 31, and the closure 6 brought down, a water-tight seal is insured by the gaskets being compressed around the resilient plug, the efficacy of the seal being multiplied by reason of the variable resiliency of the plug.

100 The plug 24 is formed with a plurality of apertures 38 and 39 adapted to receive a plurality of tubes 41 and 42, communicating with an outside source at one end, and attached to a diver's helmet 43 at the other end, 105 110 115 120 125 130

in the conventional manner, as shown in Figure 1. It will be manifest that any desired number of tubes may be employed for respiratory and signal communication with an outside source, such as a surface vessel supervising rescue operations, and threaded through the plug in any desired number of apertures, in the same manner.

At suitable points around the inside periphery of the rim 4 are provided slotted extensions 44, and around the adjacent periphery of the rim 5 at points above the slotted extensions are integrally formed posts 45, to which are pivoted threaded bolts 46. Internally threaded collars 47, formed integral with vertical shanks 48 on the ends of which are provided handles 49, are adapted to cooperate with the threaded portions on the bolts 46. In this manner, the rim 5 may be firmly secured on the rim 4 and locked in position, and a firm seal insured by operation of the adjustable bolts.

The operation of this device in connection with the apparatus disclosed in my copending application may be readily understood with reference to that invention, in which the closure herein described is substituted for the top closure of the apparatus. It will be apparent that the bottom closure may likewise be of the same construction, so that a diver may enter or leave the container from the bottom before it is sealed to a vessel. In this manner a diver may seal the lower closure while operating on the hull, so that in the event that the seal should be broken, water could not enter the body of the container.

It will of course be understood that certain conduits communicating with an outside source for the operation of the apparatus and not affecting the diver, may be connected to the body of the container as heretofore. If so desired the diver's line may be conducted through the shell of the apparatus in the same manner and a sufficient length of line arranged in the container to allow the diver to operate within a predetermined range outside the apparatus.

It will be manifest that the closure may be adapted to a wide variety of uses apart from that already described with reference to other types of submersible compartments. For example, the closures may be fitted to a specially constructed compartment in a submarine vessel whereby it would be possible for a diver to operate from such a vessel on the ocean floor.

In this connection it should be noted that the compartment could be fitted with fluid pressure devices for accustoming a diver to varying pressures. It would only be necessary to introduce air pressure by degrees until the same pressure as that exerted by the outside water was reached, at which point the diver would be able to open the closure and enter the water. By reversing the operation

the water could be exhausted, on an incoming diver entering the compartment, and the apparatus subsequently be used as a decompression chamber.

By employing a detached compartment of this character, certain of the discomforts to which divers are now almost universally subjected, could easily be overcome. In an apparatus properly fitted for introducing air and water and building up and decreasing pressure by operation from a surface vessel, a diver could enter the chamber before it was lowered in the water and by raising the air pressure become accustomed to pressure in the depths, without suffering from the chill of the water.

After this has been accomplished he could be lowered under the surface and by equalization of the water pressure without with the air pressure within the container, the closure could easily be opened, preferably after the admittance of water through suitable cocks. When the diver desired to ascend he could merely seal the closure and be brought to the surface immediately under the same pressure as that below, and subsequently be put through a decompression process either in the same container as previously described, after exhausting water and admitting air under the same pressure, or placed in an ordinary decompression chamber.

It will be apparent that the closure could also be used more simply as a tank employed in place of the usual landing stage. In this manner a diver could be lowered with the closure open, thus becoming accustomed to the increased pressure in the usual manner, and on ascension, the compartment sealed as already set forth and the diver immediately brought to the surface under the same pressure whereupon he could be subsequently removed and placed in a decompression chamber.

There is accomplished by this invention a closure for submarine compartments in which a diver attached to lines communicating with an outside source may leave or enter, when the apparatus is submerged, without leakage of water through the closure when air is substituted for the water in the compartment.

While I have shown and described the preferred embodiment of my invention, I wish it to be understood that I do not confine myself to the precise details and steps of construction herein set forth, by way of illustration, as it is apparent that many changes and variations may be made therein, by those skilled in the art, without departing from the spirit of the invention, or exceeding the scope of the appended claims.

I claim:

1. A submarine compartment comprising, means to receive a diver attached to lines communicating with an outside source, a

closure associated with the receiving means, rims formed on the receiving means and the closure, oppositely disposed depressions formed in the respective rims, corresponding resilient gaskets seated in the depressions, a plug surrounding a portion of the lines, fitted in the aperture formed by the depressions, means to lock the plug in the aperture, and means to lock the closure on the receiving means.

- 10 2. A submarine compartment comprising, means to receive a diver attached to lines communicating with an outside source, a closure mounted on the receiving means, adjacent annular rims formed on the receiving means and the closure having oppositely disposed depressions formed therein with corresponding resilient gaskets seated around the rims and in the depressions, oppositely disposed outer projections having tapered depressions formed on the rims in extension of the depressions therein, an inner projection formed on the rim of the receiving means in extension of the depression thereon, a resilient plug having a plurality of conduits adapted to receive the lines, fitted in the aperture formed by the depressions, an integral tapered collar formed on the stopper adapted to engage the seat formed by the tapered depressions in the outer projections, means to lock the plug mounted on the inner projection, and means to lock the closure on the receiving means.
- 15 3. A hatch comprising, a receiving means, a closure mounted on the receiving means, oppositely disposed depressions formed in the receiving means and the closure, means to lock the closure with respect to the sealing means, means to plug the aperture formed by the depressions, and means to lock the plugging means.
- 20 4. A hatch comprising, a receiving means, a closure mounted on the receiving means, oppositely disposed depressions formed in the receiving means and the closure, means to lock the closure with respect to the sealing means, means to plug the aperture formed by the depressions, and means to lock the plugging means.
- 25 5. A hatch comprising, a receiving means, a closure mounted on the receiving means, oppositely disposed depressions formed in the receiving means and the closure, means to lock the closure with respect to the sealing means, means to plug the aperture formed by the depressions, and means to lock the plugging means.
- 30 6. A hatch comprising, a receiving means, a closure mounted on the receiving means, oppositely disposed depressions formed in the receiving means and the closure, means to lock the closure with respect to the sealing means, means to plug the aperture formed by the depressions, and means to lock the plugging means.
- 35 7. A hatch comprising, a receiving means, a closure mounted on the receiving means, oppositely disposed depressions formed in the receiving means and the closure, means to lock the closure with respect to the sealing means, means to plug the aperture formed by the depressions, and means to lock the plugging means.
- 40 8. A hatch comprising, a receiving means, a closure mounted on the receiving means, oppositely disposed depressions formed in the receiving means and the closure, means to lock the closure with respect to the sealing means, means to plug the aperture formed by the depressions, and means to lock the plugging means.

In testimony whereof I affix my signature.
ROBERT G. MERRITT.
